UNITED STATES PATENT OFFICE

LLOYD Q. SLOCUMB, OF FERGUSON, MISSOURI

RADIO RECEIVING APPARATUS

Application filed March 27, 1925, Serial No. 18,661. Renewed July 18, 1930.

This invention relates to radio receiving apparatus, and with regard to certain more specific features to a receiving circuit and means for adjusting the same.

Among the several objects of the invention may be noted the provision of an improved reflex circuit adapted to amplify modulated radio frequency waves through a set of radio and audio frequency transformers, rectify these waves and amplify the resulting audio frequency wave through the same set of radio and audio frequency transformers, the provision of reaction and other stabilizing means for making operable the elements of said circuit, and means for readily controlling the operation of said elements.

The invention accordingly comprises the features of construction, combinations of elements, and arrangements of parts which are exemplified in the circuit and structure hereinafter described and the application of which will be indicated in the following claims.

In the accompanying drawings, in which is shown one of various possible embodiments of the invention,

Fig. 1 is a circuit diagram;

Fig. 2 is an enlarged plan view showing a combination control for a condenser and plate coils;

Fig. 3 is an elevation of Fig. 2;

Fig. 4 is a sectional detail of a rheostat; and

Fig. 5 is a plan view of the rheostat shown in Fig. 4.

Referring now more particularly to Fig. 1 there is shown a tapped coil 1 of approximately 25 turns connected in series with the usual aerial ground circuit. This coil 1 serves as the primary of a loosely coupled circuit having in it an approximately 68 turn secondary coil 2, shunted by a .00025 variable condenser 3. This condenser 3 serves tuning purposes. The primary coil 1 and the secondary coil 2 are wound upon the same form.

Inductively connected with the secondary coil 2 is a 100 turn reversed feed back or reaction coil 4 adapted to regeneratively stabilize or resonate the loosely coupled circuit.

The reaction coil 4 is connected by a lead 5 to the plate 6 of an audion tube 7.

Another lead 8 of said coil 4 connects it to one end of the primary P1 of an audio and radio frequency amplifying transformer 9. The primary P1 is shunted by a fixed condenser 10 of approximately .002 M. F. capacity, serving the usual purposes, such as to secure undistorted reception with increased volume.

My means of lead 11 primary P1 of transformer 9 is connected to a primary coil P2 of a second audio and radio frequency amplifying transformer 12 which primary coil P2 has shunted thereacross a constant .001 M. F. condenser 10^a. The condenser 10^a serves purposes similar to those of condenser 10.

The lead 11 also affords connection with the sound reproducing instrument 13. The instrument 13 is shunted by a .0005 M. F. condenser 10^b. The condenser 10^b permits passage of radio frequency but not audio frequency.

The primary coil P2 and the instrument 13 complete their circuits with the plates 91 and 93 of audion tubes 16 and 18 respectively.

The said secondary circuit, of which coil 2 is an element, has in series with said coil 2 a grid 14 of the said audion tube 7. In series with said coil 2 is also a 0-50 megohm variable resistance 19, said resistance being parallel with both a .0001 M. F. fixed condenser 20 and the secondary winding S3 of a third audio and radio frequency transformer 21. The transformer 21 serves reflexing purposes to be described. As indicated in the drawings, the transformers 9, 12 and 21 are preferably of the iron core type.

In series with said resistance 19 is a lead 22. This lead 22 has two branch leads 23 and 24. The lead 23 goes to one side of the secondary coil S1 of the first amplifying transformer 9, and the lead 24 goes to one side of the secondary coil S2 of the second amplifying transformer 12.

The secondary S1 is in series with a grid 15 of the audion tube 16 and has shunted thereacross a constant one megohm resist-

ance 95 and a .002 M. F. condenser 97 serving the usual steadyng purposes.

The secondary S2 has in series therewith the grid 17 of the audion tube 18. This secondary S2 has shunted across it a constant one megohm resistance 99 serving the usual steadyng purposes. The lead 24 is also connected to one side of a rheostat 25 which controls the 6 volt filament current of the three amplifying tubes 7, 16 and 18. The lead 24 continues from its last-named connection to the minus side of the 6 volt (low voltage) filament lighting battery 26. The battery 26 lights the filament 101 of a rectifying tube 27 of a reflex circuit connected to said loosely coupled circuit, as well as the filaments 103, 105 and 107 of tubes 7, 16 and 18 respectively. A variable resistance 39 controls the filament 101 of the tube 27.

20 A lead 28 from said lead 24 connects with the plus side of an 8 volt battery 29 (high voltage). The battery 29 is in the plate circuit of the detector or rectifying tube 27. The lead 28 has in series therewith a one 25 M. F. fixed condenser 32 which has been found to quiet the battery noises.

The minus side of battery 29 connects with the plus side of battery 26 and also to the minus side of a high voltage battery 30 by way of lead 44. Battery 30 has about 110 volts pressure and is used on the said loosely coupled amplifying circuit. Shunted across battery 30 is a fixed one M. F. condenser 109. The positive side of the battery 30, by means of a lead 36, connects with a one turn primary winding 33 which controls the circuit of the detector tube 27. A return lead 35 from said coil 33 is connected to the aforesaid lead 11. The lead 11, as has been described connects with the plates of tubes 7, 16 and 18 in the first named loose coupled circuit.

The minus side of battery 30 is connected by means of lead 44 with the positive side of battery 26. The lead 44 serves as a common return for the current which goes to the filament of the tubes 7, 16 and 18 from the minus side of the battery 26.

Cooperating with the single turn primary coil 33 is a 68 turn secondary coil 34. One end of the coil 34 leads to a combination grid leak and fixed condenser 37. The combination 37 has its component values fixed by the particular tube being used in the detector circuit. The combination 37 is in series with a grid 38 of the detector tube 27.

The other side of the secondary winding 34 leads to the plus side of the battery 26, already mentioned in connection with the filament lighting circuits.

The secondary coil or winding 34 is shunted by a variable condenser 51 of approximately .00025 M. F. capacity serving tuning purposes.

65 A reaction coil 50 cooperating with the sec-

ondary coil 34 leads, on one side, to the plate 40 of detector tube 27 and on the other side leads to the plus side of battery 29 by way of the primary P3 of the said third audio and radio frequency transformer 21. The primary P3 is shunted by a fixed condenser 41 of approximately .004 M. F. capacity for permitting passage of radio frequency.

Before considering the operation of this entire circuit it should be noted that the transformers 9, 12, and 21 are of the continuous core type, and both radio and audio frequencies may be transformed therein.

The action is as follows:

Modulated radio frequencies or signals are received in coil 1 by means of the usual aerial circuit. These signals are transmitted to, or induced in coil 2 which feeds into tube 7. The output of the plate 6 or tube 7 feeds through the reaction coil 4, some of the energy being used preferably to stabilize the amplifying circuit. However it may be desirable to amplify it sometimes.

The balance of the energy passes out through the transformer 9 into the tube 16. 90 By means of the transformer 9 amplified radio and audio frequencies are transmitted to the tube 16.

The output of tube 16 passes through the transformer 12 which again transmits amplified audio and radio frequencies to the tube 18.

The amplified modulated radio frequency output of tube 18 by-passes the phones through the condenser 10b and feeds into the single turn loop 33.

It should be noted that the plates of tubes 7, 16 and 18 are arranged in cascade and feed into lines 11 and 35 so that if there is a tendency for one tube to oscillate it will be steadied by the others.

The primary coil 33 feeds into the tuned circuit of secondary coil 34. The coil 34 is provided with the reaction coil 50 for the purpose of boosting or stabilizing oscillations. It is also shunted with the usual variable condenser 51 of about .00025 M. F. capacity.

The tube 27 rectifies the input wave and an audio frequency is fed through the transformer 21, through the resistance 19 and back into tube 7.

From tube 7 the audio frequency wave traverses the tubes 7, 16 and 18 as well as the transformers 9 and 12. Since the said transformers operate on electromagnetic principles as well as electrostatic, this wave readily passes through them.

The aforesaid process of amplification is again gone through by the audio frequency wave and it appears at the sound reproducing instrument 13, not being able to pass through the condenser.

The radio frequency which appears at the primary P3 of transformer 21 was shunted

through the condenser 41. It is believed however, that some leaks over to the loose coupled circuit of coil 2 and assists the original impressed radio frequency wave, thereby compensating for the usual inefficient action of continuous core transformers on radio frequency waves. Of course there is little difficulty experienced with these transformers on audio frequencies.

10 Thus it is evident that this complete circuit provides means for amplifying both radio and audio frequencies with the same set of transformers. A number of parts are eliminated with equal or better volumes and distance attained by the set.

15 The resistance 19 is an effective throttling device for stabilizing the loose coupled circuit of coil 2.

20 Attention is called to the fact that all lamp filaments are cascaded from the battery 26 but separate resistance control rheostats are provided for the rectifying tube 27 and the amplifying tubes of the loose coupled circuit of coil 2.

25 In order to provide easy control of this circuit certain novel features have been introduced.

30 In tuning the circuits of coils 2 and 34 the two condensers 3 and 51 must be adjusted. Also, the coils 4 and 50, which are of the plate type must be adjusted. In order to facilitate making these four adjustments with two hands at one operation I provide the combination depicted in Figs. 2 and 3. By 35 way of example the elements of the first loose coupled circuit of coil 2 are used.

35 The variable condenser 3 is fixed to a slide- able plate 60. Said plate 60 mounted slide- ably in guides 61 and 62. These guides are fastened to a suitable element 70 of the circuit equipment. The adjusting shaft 66 upon which is mounted the adjusting dial 67 ex- tends through a slot 68 in said element 70.

40 Mounted on the condenser by means of one of the spacer bolts 64 and spaced away from said condenser by means of a spacer collar 65 is the reacting coil 4 which is of the plate type. Below this coil 4, but not in movable connection therewith is the combination plate of coils 1 and 2.

45 Obviously, adjustments may be made on the condenser 3 with the hand by means of the dial 67 and simultaneously with the same hand the coil 4 may be slidably arranged in various positions with respect to the coils 1 and 2.

50 A like arrangement is provided for the condenser 51 and coils 50, 34 and 33 and so the four adjustments may be made at once.

55 An extension 71 fastened to the condenser dials permits of fine adjustment of the condensers without causing coil adjustments.

60 The rheostat 19, since it is a critical element of the circuit is of the graphitic type shown in Figs. 4 and 5 where an insulating

disc 75 is shown mounted upon a shaft 76. It is mounted between two conducting discs 76 and 77. Between these discs and in contact therewith is a circular wedge of graphite 78 mounted upon said insulating disc. A 75 wiper 79 forms one terminal of the apparatus and transmits current to the graphite 78 when in contact therewith and the graphite transmits an amount of current to the discs and consequently to the shaft 80 upon which 75 they are mounted proportional to the thickness of graphite at a given point of contact of the wiper. A fine control is thus established. The shaft 80 to which discs 76 and 77 are fastened forms the other terminal 80 of the apparatus. A notch at the end of the graphite wedge audibly indicates when contact has been broken between the wiper 79 and the wedge 78 which is to say, when all the resistance is in. This device serves as an 85 effective, closely controllable damping apparatus. The notch 81 also serves to keep the wiper 79 from spreading the fine feather edge of graphite 78 over the uncoated surface of the disc 75. It is intended that there 90 should be a portion of the disc 75 always clean of any carbon so that an extremely high resistance may be obtained by allowing the brush 79 to contact with pure uncoated insulating material or fiber 75. The effectiveness of the device is thus enhanced. In view of the above, it will be seen that the several 95 objects of the invention are achieved and other advantageous results attained.

As many changes could be made in carrying out the above constructions without departing from the scope of the invention, it is intended that all matter contained in the above description or shown in the accompanying drawings shall be interpreted as 100 105 illustrative and not in a limiting sense.

I claim:

1. In a receiving circuit including a sound reproducing device, the combination of an aerial ground circuit; a loose coupled circuit 110 cooperating inductively with the aerial circuit by way of a secondary coil and a reaction coil for the secondary coil; said loose coupled circuit including a stabilizing resistance, a plurality of audion tubes and 115 audio- and radio-amplifying transformers, a tuned circuit, a tuning primary winding for said tuned circuit, means for connecting said reaction coil in parallel through the primaries of said transformers and through 120 said sound reproducing device to the plates of at least some of said tubes, the grids of said tubes being in parallel circuit with said secondary coil by way of the secondaries of said transformers; a battery connecting with 125 the primary winding for the tuned circuit and supplying the filaments of said tubes in parallel; a tuned secondary coil for said tuning primary winding, a reaction coil there- 130 for; said tuned circuit including a rectifying

tube, and means for supplying said loose coupled circuit with energy from said tuned circuit by way of said stabilizing resistance.

2. In a receiving circuit including a sound reproducing device, the combination of an aerial ground circuit; a loose coupled circuit cooperating inductively with the aerial circuit by way of a secondary coil and a reaction coil for the secondary coil; said loose coupled circuit including a plurality of audion tubes and audio- and radio-amplifying transformers, plates, filaments and grids for said tubes, a tuned circuit, a tuning primary winding for said tuned circuit, means for connecting said reaction coil through the primaries of said transformers and through said reproducing device to the plates of at least some of said tubes, the grids of said tubes being in circuit with said secondary coil by way of the secondaries of said transformers; a battery connecting with the primary winding for the tuned circuit and supplying the filaments of said tubes; a tuned secondary coil for said tuning primary winding, a reaction coil therefor; said tuned circuit including a rectifying tube, and means for supplying said loose coupled circuit with energy from said tuned circuit.

In testimony whereof, I have signed my name to this specification this 24th day of March, 1925.

LLOYD Q. SLOCUMB.
